D. E. HARDING

LEATHER BOARDING MACHINE

Filed April 29, 1922

UNITED STATES PATENT OFFICE.

DANA E. HARDING, OF DANVERS, MASSACHUSETTS.

LEATHER-BOARDING MACHINE.

Application filed April 29, 1922. Serial No. 557,248.

To all whom it may concern:

Be it known that I, DANA E. HARDING, a citizen of the United States, residing at Danvers, in the county of Essex and State of Massachusetts, have invented new and useful Improvements in Leather-Boarding Machines, of which the following is a specification.

The present invention relates to a machine for performing the operation on skins and pieces of leather, known as boarding, by which fine wrinkles are formed throughout the surface of the grain side of the leather. Heretofore, this operation has generally been performed by hand, the workman folding the leather piece and laying it in the folded condition on a table, and then placing a board on the upper side of the folded piece and rubbing the board across the fold, whereby the upper side of the piece is caused to slide over the lower part and the position of the fold is progressively shifted from its original location out to the edge of the piece. The workman meanwhile constantly maintains pressure on the board, which makes the fold a sharp one. When one half of the piece has been treated in this fashion, it is again folded at the same place and laid on the table in a reversed position, with that side uppermost which previously was underneath, and the same operation is repeated. The result is known in the trade, as leather which has been boarded one way. For some purposes, it is required that the leather be boarded two ways, which means that after having been treated as thus described, it is folded on a line at right angles to the first fold, and the same operations are carried out again on the new fold.

The hand operation is fatiguing and slow, and the output of each operator is necessarily limited. It is an unusually able operator who can produce as many as twenty-five dozen sides of upper leather boarded one way during a single working day. It has been suggested that a greater and more rapid output of boarded leather for each operator employed, could be obtained if suitable machines for performing the boarding operation were available; and although several designs for machines of this sort have been made, the result has not yet been achieved of furnishing to the trade a practical machine capable of producing satisfactory work

and being at the same time free from complication and inexpensive to build. 55

My object in making the present invention has been to devise a machine which is automatic in operation, except for the insertion and removal of the leather being operated on, which is able to produce work of as good quality as, or better than, that of the hand method, which shall be more rapid in its action than the hand method, and at the same time is simple in character and relatively inexpensive to build and maintain. A machine meeting the conditions and serving the objects above set forth, is described in the following specification and illustrated in the drawings referred to therein; and it is in such a machine and equivalent structures coming within the scope of the appended claims, that my present invention resides. 60

In the drawings, Figure 1 is a side elevation of the particular machine above referred to. 70

Figure 2 is a plan view of the machine.

Figure 3 is a cross-section on line 3—3 of Figure 1, showing in elevation the parts at the left of said line. 80

Figure 4 is a detail showing in side elevation the cam by which the board is controlled.

Like reference characters designate the same parts wherever they occur in the figures. 85

In this machine the numeral 1 represents a table on which the folded skin and other pieces of leather are laid when being operated on. The pieces so placed, are acted upon by a tool 2 which is similar to the hand implement known in the art as a "board," and will be called a board in this specification. It is essentially a plate having a flat under-surface of a length and width sufficient for the purpose in view, and it may be made of any suitable material. In practice, I have made it of boards fitted together edge to edge, and secured by cleats or battens. This board is connected to an arm 3, which is pivoted on a pin 4, secured in a carriage or slide 5, which is adapted to travel in or on guideways 6. Arm 3 may be made of any material secured in any suitable way to the board. In the machine here shown, it is a wooden beam secured to the board by an intermediate block 7. There are two guideways 6 arranged parallel to each other at 90

100

105

opposite sides of the carriage 5, and having grooves in their sides which face one another, to receive ribs 8 on the carriage or slide, as shown in Figure 3. The carriage 5 may be of any suitable construction, but is conveniently made of two side members to which the numeral 5 is directly applied, the pivot 4, a second pivot 9, and any desired number of cross braces 10. The pivots 4, 9, 10 and cross braces 10, are secured at their opposite ends in the side plates of the carriage and brace such plates, holding them at a given distance apart. They may be formed with shoulders at the inner sides of the 15 plates, and with nuts or other fastening means at the outer sides.

The pivot 9 is the wrist pin for a connecting rod 11 which is pivoted to a crank pin 12 on a fly wheel 13 mounted on a shaft 14, which 20 is driven by a belt pulley or other suitable means of well understood character, and therefore not here shown in detail. On the end of the connecting rod, and preferably secured to the upper side of the box on said 25 rod which embraces the wrist pin 9, is a cam 15, which acts to control the board in a manner which I will now describe.

The arm of beam 3 carrying the board, has an extension arm 16, to which is secured by 30 means of a bracket or stirrup 17 a trundle roll 18 arranged to bear on the surface of cam 15. Across the opposite side of arm 16 is placed a bar 19, the ends of which overhang the side plates of the carriage 5. Link 35 rods 20 pass through the ends of bar 19 and are connected by pivots 21 to the side plates of the carriage. Between the bar 19 and abutments 22 on the upper ends of the bars 20, are springs 23 which act on the arm 16 with a 40 tendency to raise the board and to hold the trundle roll in contact with the cam 15. The adjustments 22 are adjustable on the link rods, so as to vary and regulate the pressure with which the springs thus act; and 45 the stirrup and strap 17 carrying the trundle roll is adjustable up and down on the arm 16, so as to control the position of the board with reference to the cam. For the purpose of this adjustment, the strap or holder 17 50 is held by clamp screws 24, which pass through elongated holes and enter the arm 16, thus permitting a limited up and down adjustment of the strap and serving to clamp it in any adjustment.

55 Referring now particularly to the cam 15, the same has two distinct parts, 25 and 26 in its surface, the former being an incline having a raising and lowering function, and the other being a dwell. The relations 60 and further characteristics of these parts can best be explained in connection with the description of operation occurring further on in this specification.

65 For the rest, the mechanical construction of the machine comprises a frame or base

structure of any suitable character to support the table 1, at a height convenient for the use of the operator in placing and removing the work pieces, and to support the guideways 6 and the shaft 14 at the proper heights and in the proper locations, to move the board across the table when acting on the work and to enable the board to be raised and lowered by the action of the cam 15.

70 The operation of the machine is thus:—

Assuming that the fly wheel turns in the direction of the arrow beside it in Figure 1, then the cam dwell 26 is so formed that throughout the extent of the rearward movement of the carriage and board (that from left to right in Figure 1 of the drawing), it causes no displacement of the board, but holds the board continuously in the position

where the latter will exert pressure upon the work. When the crank is in the neighborhood of the rear dead point (whether exactly at this point, or slightly before or after it, is immaterial) the cam incline 25 begins to pass over the trundle roll 18, and as the surface of this incline recedes when the connecting rod swings in the manner now taking place, the springs 23 are able to 80

lift the board, relieving the pressure of the latter on the work, and enabling the operator to remove the work piece and refold and replace it upon the table, or to substitute a new piece. The cam surface 25 is so shaped that the board is held at a sufficient height above the table for the removal and replacement of the work throughout the forward travel, or a large enough proportion of that travel to permit the necessary manipulation of the work. As the crank 90

rises from its lowermost position in approaching the forward dead point, the cam surface 25, which with reversal of the wrist pin swing of the connecting rod becomes a rising surface, causes the board to be lowered and finally to press on the work at or about the commencement of the rearward stroke. It will be noted that the pressure of the board on the work is applied positively through the cam and roll. This pressure may be varied, according to the thickness and nature of the leather, by the adjustment 100 previously described of the roll holder 17. This mode of applying the pressure is an important feature of the invention, for it enables a very accurately graded pressure, 110

which can be made practically as severe as desired, to be exerted on the folded work piece during the boarding action. Thus a greater pressure may be exerted on the work than can be applied by the muscular strength of the operator, the fold is compressed sharply, and the grain produced by the boarding made as fine and even as may be desired.

115 It follows from these characteristics that the quality of the work must be as good as 120

- that of hand operation and may be better, that it is uniform in quality, because not subject to the variation due to the fatigue of the operator, and that the output for each operator is largely increased, because the machine may be made to run as rapidly as the operator can remove and replace work pieces during the forward travel of the board.
- 10 It will be apparent that various changes in structure and arrangement of the parts, and substitution of equivalent devices, may be made in the machine without departing from the spirit of the invention or exceeding 15 the scope of the claims.

What I claim and desire to secure by Letters Patent is:

1. A boarding machine comprising a table on which folded work pieces may be placed, 20 a board overlying said table and being adapted to cooperate with said table in performing the operation of boarding leather, a carriage to which said board is connected, and means for driving said carriage back 25 and forth in a path approximately parallel to the plane of the table, said driving means having provisions for causing the board to be held above the table during its travel in one direction and to be held down upon the 30 work during its travel in the opposite direction.

2. A boarding machine comprising a table, having a flat supporting surface on which folded work pieces may be laid, a board 35 having a flat under-surface adapted to bear on the work pieces so placed and being adapted to cooperate with said table in performing the operation of boarding leather, a carriage guided to move in a path parallel 40 to the plane of the table and to which said board is pivoted so as to overhang the table, a driving mechanism for the table comprising a crank and connecting rod having a wrist connection with the carriage, whereby 45 the board is moved back and forth, said connecting rod and the board having complementary abutments arranged to raise the board during the travel of the carriage in one direction, and to permit the board to 50 occupy a lowered position in engagement with the work in such travel in the opposite direction.

3. A boarding machine comprising a table, a board overhanging said table and being 55 adapted to cooperate with said table in performing the operation of boarding leather, a carriage arranged to travel approximately parallel to the surface of the table and to which the board is connected so as to move 60 in unison therewith, a connecting rod having a wrist connection with the carriage, and a rotating crank to which the connecting rod is pivoted and by which the connecting rod, the carriage and the board are 65 moved back and forth, said connecting rod

and board having complementary means actuated by the changing angularity of the rod to raise the board when the crank is near one dead point, and to lower it when the crank is near the opposite dead point.

4. A boarding machine comprising a table, a carriage reciprocable toward the end of the table, a board pivoted to the carriage in position to overhang the table and being adapted to cooperate with said table in performing the operation of boarding leather, complementary means acting between said carriage and board tending to raise the board, a connecting rod having a wrist connection with the carriage, a crank joined to said connecting rod, and a cam carried by the connecting rod and acting upon an abutment associated with the board, said cam having a surface arranged to exert pressure on the abutment holding the board down during the travel of the carriage in one direction, and having a raising and lowering surface arranged to permit the board to be raised and so held while the carriage travels in the opposite direction.

5. A leather boarding machine comprising a table adapted to receive folded pieces of leather, a board adapted to cooperate with said table in performing the operation of boarding leather, a carriage movable back and fourth parallel to the surface of said table and to which said board is pivoted, a lever arm associated with the board, a spring acting between said arm and the carriage tending to raise the board from the table, a cam abutment mounted on said arm and being adjustable thereon in approximately the directions in which said arm swings, a rotating crank for giving motion to said carriage, a connecting rod between the crank and carriage having a wrist connection with the latter, a cam carried by the said connecting rod and arranged to act on said cam abutment, said cam being so formed that throughout a large part of the travel of the carriage, it applies force positively to the board in the direction pressing it toward the table, and the cam having another part which is arranged to coact with said abutment during the travel of the carriage in the opposite direction, and is so formed that during part of such opposite travel, it permits rise of the board by the action of said spring, and during the last part of such travel it causes the board to be lowered.

6. A leather boarding machine comprising a table adapted to support a folded skin, a board complementary to the table having an area and surface adapting it to perform in association with said table the operation of boarding such a skin, a carriage movable back and forth parallel to the plane of said table and being displaced horizontally therefrom, an arm pivoted to

the carriage and to which said board is secured, a driving crank, a connecting rod joined to said crank and carriage, a cam mounted on said connecting rod so as to rock therewith, and a cam abutment rigidly connected with said arm and engaged with the cam, said cam and abutment being arranged and constructed to hold the board toward the table with a positive action during the travel of the carriage in one direction, and to release the board, permitting its separation from the table, during the travel of the carriage in the opposite direction.

7. A leather boarding machine comprising a table adapted to support a folded skin, a board complementary to the table having an area and surface adapting it to perform in association with said table the operation of boarding such a skin, a carriage movable back and forth parallel to the plane of said table and being displaced horizontally therefrom, an arm pivoted to the

carriage and to which said board is secured, a driving crank, a connecting rod joined to said crank and carriage, a cam mounted on said connecting rod so as to rock therewith, a cam abutment rigidly connected with said arm and engaged with the cam, and a spring interposed between said connecting rod and arm arranged to exert force tending to move the abutment toward the cam and at the same time to separate the board from the table, the cam being constructed with a rise which acts on the abutment and positively presses the board toward the table during the travel of the carriage in one direction and with a relieved surface which comes opposite the abutment and permits said spring to displace the board from the table during the travel of the carriage in the opposite direction.

In testimony whereof I have affixed my signature.

DANA E. HARDING.
